(57) **CLAIM**

I claim the ornamental design for a light, as shown and described.

DESCRIPTION

FIG. 1 is a perspective view of a light embodying the invention.

FIG. 2 is a front view of the light of FIG. 1.

FIG. 3 is a rear view of the light of FIG. 1.

FIG. 4 is a left side view of the light of FIG. 1.

FIG. 5 is a right side view of the light of FIG. 1.

FIG. 6 is a top view of the light of FIG. 1; and,

FIG. 7 is a bottom view of the light of FIG. 1.

The broken lines depict portions of the light that form no part of the claimed design.
